UNITED STATES PATENT OFFICE.

WILLIAM H. T. THORNHILL, OF PHILADELPHIA, PENNSYLVANIA.

APPARATUS FOR FORGING BUCKET-WHEELS.

1,190,817.

Specification of Letters Patent.

Patented July 11, 1916.

Original application filed February 23, 1915, Serial No. 9,863. Divided and this application filed March 23, 1916. Serial No. 86,185.

To all whom it may concern:

Be it known that I, WILLIAM H. T. THORNHILL, a citizen of the United States, residing at Philadelphia, county of Philadelphia, and State of Pennsylvania, have invented a new and useful Improvement in Apparatus for Forging Bucket-Wheels, of which the following is a full, clear, and exact description, reference being had to the accompanying drawings, which form a part of this specification.

The forging of bucket wheels by apparatus in most general use involves the employment of cumbersome and expensive dies, whose life is short, and special dies are necessary for each size of wheel. The operation is therefore quite expensive. A process and apparatus are, however, known whereby comparatively small and inexpensive dies of relatively great durability may be utilized in the manufacture of wheels of different sizes. In this process a blank with a central hole is placed upon an anvil die having a pin which projects through the hole. One wall of the hole is maintained against the pin and an upper die compresses the metal of the blank along a radially extending section thereof adjacent to said wall, the blank being turned from time to time to allow the upper die to compress other radial sections, the operation being continued until the entire blank is forged. This process displaces the metal mainly tangentially or at right angles to the radius under the die, thus increasing the diameter of the wheel. It also reduces the thickness of the wheel. This process, while operative to effect the manufacture of different sized wheels unprovided with rims of greater thickness than the webs, is not, in and of itself, operative to effect the complete manufacture of different sized wheels provided with rims of special thickness.

The object of my invention is to modify and improve this known apparatus and process so as to forge wheels of different diameter having rims of greater thickness than the web.

The invention has for another object the manufacture, without change of dies, of wheels in which the difference between thickness of web and thickness of hub is variable.

In the drawings, which illustrates a preferred embodiment of my improved appa-

ratus for carrying out my improved process: Figure 1 is a plan view of the lower die and carriage. Fig. 2 is a side view of the apparatus, with a wheel blank shaped as a result of the first forging operation. Fig. 3 is a section on line 3—3 of Fig. 1. Fig. 4 is a section showing an end view of the dies. Fig. 5 is a side view similar to Fig. 2 showing the carriage in a different position, with a wheel blank shaped as a result of the concluding forging operation.

a represents a stationary anvil or lower die. The upper die *b* is shouldered on its inner face to receive a removable die section *c* held in place by studs *d*.

Adjacent to the inner face of die *a* is a carriage *e*. This carriage constitutes, in effect, part of the lower die, as clearly appears hereinafter. At the beginning of the forging operation, the carriage preferably abuts against the lower die so as to be continuous therewith. The carriage *e* is slideable horizontally toward and from the stationary lower die along ways *f*, which rest on removable blocks *h* within a support *g*. The support and ways are secured together by means of bolts *i* extending between flanges *g'*, *f'*. The ways *f* and the carriage *e* are provided with rows of holes *k* and *j* respectively. The holes in one member are spaced differently from the holes in the other member. Thus, I have the holes *k* spaced at uniform distances apart and the holes *j* at irregular distances apart. At different horizontal positions of the carriage different pairs of holes align, and the carriage is maintained in any adjusted position at which the holes register by means of pins *m*. The carriage is socketed on its face to receive the enlarged lower end of a removable pin *n*. The ways *f* are vertically adjustable in the support *g*. The height of the ways is determined by the thickness of the blocks *h*.

In the initial operation the carriage is in the position shown in Figs. 1 and 2, and a blank, of disk shape with a center hole, is placed on the carriage. One radially extending section of the blank will overlie the lower die *a*. The wall of the hole in the blank that is nearest the dies *a* and *b* is maintained against the pin *n*. The upper die, by suitable mechanism, is lifted and moved down or allowed to drop, and alternately therewith the blank is turned step by

step, until the dies have acted upon the entire circumference of the wheel, thereby shaping the same to the form shown at α in Fig. 2. This operation increases the diameter of the wheel, shapes the wheel at the junction between hub and web, and reduces the thickness of the wheel. The pins m are now withdrawn and the carriage e is moved horizontally in the ways f away from the die α . The distance to which the carriage will be moved depends upon the extent to which it is desired to enlarge the diameter of the wheel in the next operation. The pins m are now reinserted. The upper die is now reciprocated and the wheel turned as in the first forging operation. In the second operation, however, the wall of the hole farthest from the dies is maintained against the pin. There is preferably, no further reduction in the thickness of the hub or of that part of the web adjacent thereto, but the metal of the rim is compressed and also displaced outwardly, thus substantially increasing the radial dimensions of the web and decreasing the width and thickness of the rim, as shown at γ , Fig. 5. If the second operation is the final operation, the rim will have the approximate shape and thickness required for the rough forging.

The apparatus permits, if necessary, of one or more additional operations. The number of operations depends upon the desired diameter of the finished wheel and upon the extent to which it is desired to increase the diameter of the wheel in a single operation.

If, at the conclusion of the final wheel expanding operation, it is found that the rim is of too great thickness, the wheel can be moved over into position to bring the edge of the rim underneath the upper die, and the rim alone may then be compressed to the proper thickness by revolving the wheel step by step between reciprocations of the upper die, as in the previous operations.

To effect the forging of a wheel having a hub of relatively great thickness, the ways f are lowered by removing the blocks g or by substituting thinner blocks. The die section c is also removed and a thinner plate substituted.

I do not herein claim the process for forg-

ing bucket wheels herein set forth as the same forms the subject matter of an application filed February 23d, 1915, Serial No. 9,863 of which this application is a division.

Having now fully described my invention, what I claim and desire to protect by Letters Patent is:

1. Means for forging wheels provided with a central hole, comprising a carriage, a lower die forming, with the carriage, a support for a part of the blank, an abutment on the carriage adapted to extend through the hole in the blank, an upper die, and ways in which the carriage is movable horizontally toward and from the lower die.

2. Means for forging wheels provided with a central hole, comprising an upper die, a lower die, a carriage forming with the lower die a support for a part of the blank and adjustable horizontally toward and from the lower die and also adjustable vertically, and an abutment on the adjustable carriage adapted to extend through the hole in the blank.

3. Means for forging wheels provided with a central hole, comprising a lower die, a horizontally adjustable carriage alongside the lower die, an abutment on the adjustable carriage adapted to extend through the hole in the blank, and an upper die adapted to extend over the lower die and also over a part of the carriage when the latter is in horizontal position nearest the lower die.

4. Means for forging wheels provided with a central hole, comprising a carriage, a lower die forming with the carriage a support for a part of the blank, an abutment on the carriage adapted to extend through the hole in the blank, an upper die, ways in which the carriage is movable horizontally toward and from the lower die, said carriage and ways having rows of holes differentially spaced, and a pin adapted to engage alining holes in the carriage and ways respectively.

In testimony of which invention, I have hereunto set my hand, at Philadelphia, on this 17th day of March, 1916.

WILLIAM H. T. THORNHILL.
